POUNDING TOY OR SIMILAR ARTICLE

Gilbert G. Southwick, Plainfield, N. J., assignor to Childhood Interests, Inc., Roselle Park, N. J., a corporation of New Jersey

Application January 30, 1956, Serial No. 39,968

Term of patent 14 years

(Cl. D34—15)

FIG.1.

FIG.2.

FIG.3.

FIG.4.

Fig. 1 is a plan view of the pounding toy or similar article showing my new design;

Fig. 2 is a side elevational view thereof;

Fig. 3 is a fragmentary end elevational view thereof, a portion being omitted for convenience in illustration; and

Fig. 4 is a sectional view thereof, taken along the line 4—4 of Fig. 1

The dominant features of my new design are shown in solid lines in the drawing.

I claim:

The ornamental design for a pounding toy or similar article, as shown and described.
